RELIQUEFACTION SYSTEM FOR LIQUEFIED GASES

Alexis Pastuhov, Harvard, Mass., assignor, by mesne assignments, to Conch International Methane Limited, Nassau, Bahamas, a corporation of the Bahamas

Filed Jan. 16, 1958, Ser. No. 709,290

3 Claims. (Cl. 62—54)

This invention relates to the storage or transportation of low boiling liquefied gases and it relates more particularly to a means employed in combination with such tanks as are used in the storage or transportation of a low boiling liquefied gas for the recovery of the vapors released by such liquids in storage or transportation and for the return of the vapors in a liquefied form to the respective tank from which it was released.

Although extensive work has been done in the fabrication of an insulated tank to minimize heat leaks into the tank to cause vaporization of the cold boiling liquefied gas contained therein, absolute elimination of heat leaks has not been achieved and may not be capable of achievement. Thus provision must be made for the handling of the vapors that are released by the liquid housed in the storage container. It is well known that as such vapors are released by the container, pressure builds up in the container and that means must be provided for the relief of pressure to prevent build-up to dangerous levels.

If the vapor is of little economical value, the most expedient means for the relief of built-up pressure is to employ a pressure relief valve for each tank which will operate to vent off the vapors into the atmosphere when a predetermined pressure level is reached within the tank. If, on the other hand, the vapors are of economical importance, or have a commercial value which exceeds their cost of recovery or otherwise cannot safely be released to the atmosphere, it is desirable to recover the vapor as a liquefied material for return to the storage tank. Hence it is desirable to have a relatively simple and inexpensive system for recovering and recondensing the vapor so that it can be returned to the liquid storage tank.

In such cases as shipboard installations, where it may be desirable to have a number of insulated tanks suitable for carrying liquefied gases, as in the system described in the copending Henry application Ser. No. 582,965 for the transportation of liquefied natural gas in large volume in storage tanks of large capacity mounted within the hold of the ship, it would be inconvenient and expensive to provide each tank with its own individual recovery system.

Further, the limited space available on the ship would render such multiple units impractical from the standpoint of availability of space. On the other hand, if only a single system were to be employed for the recovery and reliquefaction of the vapors escaping from all of the tanks, it would be difficult to proportion the reliquefied gas for return to the tanks in the amount vaporized since some tanks would be characterized by greater heat leaks than others, depending upon its location in the ship and depending upon the characteristics of the tank and its insulation. Thus there would be a possibility of overflowing some of the tanks or creating an unbalance in the tanks and in the ship. Further, it would be impossible to make use of the tanks for the storage of different liquefied gases therein. Thus, in on-ship reliquefaction

5 for the recovery of released vapors, there is a need for a simple, efficient and safe system for the recovery of vapors released from the tanks and for return of the reliquefied vapors to the tanks in proportion to the amount of vapors released so as to provide for the characteristics of an individual recovery system for each tank without the expense and other inconveniences of a multiple recovery system thereby to enable vapors of each tank to remain divorced from the vapors of another tank so that the vapors of each tank will be capable of recovery and reliquefaction for return to the tank from which they were released.

10 It is therefore an object of this invention to provide a system which permits the storage or shipment of large quantities of liquefied gases over an extended period of time.

15 It is another object to provide such a system which permits a simple and economical recovery of vapors released during extended storage or shipment.

20 It is a further object to provide a recovery and recondensing system which will serve one or more liquefied gas tanks without introducing the problem of metering the recondensed vapors back to the liquid containing tanks.

25 It is still another object to provide a recovery and recondensing system which may be capable of application to the storage and handling of more than one liquefied gas.

30 These and other objects and advantages of this invention will hereinafter appear and for purposes of illustration, but not of limitation, an embodiment of this invention is shown in the accompanying drawing in which—

35 Figure 1 is a flow diagram of a typical cycle of a system embodying the features of this invention.

40 By the process of this invention, there is provided a recovery system consisting of a bath of a liquid refrigerant in which is submerged a condensing coil for each tank bringing, in a closed system, vaporized gases from the storage tank and returning the condensed and liquefied gases to the same tank. Such a system as disclosed by this invention permits one recovery system to serve on or more tanks using a relatively simple thermo-dynamic cycle.

45 The operation of the process of this invention may be more fully explained with reference to Figure 1 in which a cycle is shown wherein gas is recovered and recondensed from a plurality of separated tanks containing a liquefied gas, as represented by the three tanks which, for purposes of illustration, will be assumed to contain liquefied natural gas at about atmospheric pressure having a boiling point within the range of —240° F. to —258° F.

50 In Figure 1 liquefied gas 12 is stored in tank 10 which, in turn, is surrounded by any suitable form of insulation 11 (or by an evacuated space), and which is equipped with a filling line 33 having a valve 32 for the introduction of the liquefied gas and which is equipped with a draw-off line 30 incorporating a valve 31 for the removal of liquefied gas from the tank. While line 30 is shown as an outlet at the bottom, it is often preferred to have the line extend upwardly from the bottom through the top of the tank. Generally, it will be impractical completely to fill the tank with liquefied gas. Thus a space 13 will remain at the top of the tank which will be filled by vapor released from the liquid. As heat leaks into the tank, additional liquid will be vaporized and will operate to build up the pressure in the tank unless relieved. While the tanks are constructed to take some pressure, it is undesirable and economically impractical in many instances to construct tanks of large capacity to take high pressures. To maintain the pressure in area 13 at a safe level, the excess gas formed by vaporization

3
is led out of the tank 10 through a line 14 to a recon-
densing system. A pressure regulating valve 15 is pro-
vided in the line 14 to maintain the pressure in the tank
10 and the area 13. Line 14 may also be provided with
an auxiliary blower 16 to assist in circulating the gas
through the recondensing system.

The recondensing system comprises a tank 19 confined
within an insulation 20. The tank is partially filled with
a liquid 21 selected to be at a temperature sufficiently
low enough to recondense the gases entering through line
14 into the condensing coils 17 which are immersed in
the liquid 21. The temperature of the liquid should not
be so low as to cause solidification of the liquid con-
densed in the coils 17. Thus the liquid 21 should be
characterized by a temperature below the condensation
temperature for the gas but above its solidification tem-
perature. The liquid 21 does not fill the tank 19 so as
to leave an area 22, much like the area 13 in the storage
tank, to contain vapor formed by the vaporization of the
liquid 21 upon the absorption of heat from the condens-
ing vapors in the condensing coils 17.

The liquefied gases 12 (in the storage tank) and 21
(in the condensing tank) may be the same. In such in-
stance, sufficient differential in temperatures to effect
condensation of the gas from the storage tank may be
achieved by maintaining a predetermined pressure in area
13 of the storage tank and a somewhat lower pressure
in the area 22 of the recondensing tank. The pressure
difference in these two areas can be so adjusted as to
fix the boiling points of the liquefied gases and thereby
control the temperatures within the relatively small limits
required. For example, if liquid methane were being
stored in the tank 10, then the area 13 could be main-
tained under a pressure of about 16 p.s.i.a. while the
pressure in the tank 19 could be maintained at about 10
p.s.i.a. This would provide for a temperature differential
of about 12° F., a differential sufficient to recondense
methane gas entering condensing coils 17 and to return
it via return line 18 as a liquid to the liquid storage tank.

Alternately, the liquid 21 in which the condensing coil
17 is immersed may be a liquid different from the liquid
12 which is stored or shipped. Because of the low tem-
perature requirement, cooling liquid 21 is conveniently
a liquefied gas, such as liquid nitrogen, liquid air, liquid
helium or the like. The choice of the liquid to be used
will of course depend upon the liquefied gas 12 which is
being stored. Normally, if the liquid 21 is not the same
as liquid 12, then liquid 21 should have a boiling point
a little below the boiling point of the liquid 12, unless, as
in the case where the liquids are identical, a sufficient
temperature differential can be achieved by proper con-
trol of pressures in the areas 13 and 22.

Alternate methods for returning the liquefied gas from
the recondensing system to the tanks 10 may be employed
instead of the blower 16 used to force the gas through
the coil 17 and into the return line 18. A gravity feed
system may be provided if the recondensing system is
elevated safely above the tank 10 and the coils 17 and
so oriented as to permit the liquid to drain out as it is
formed. It is also possible to make use of a liquid pump
in the return line 18 to direct the liquefied gas to the
tank 10.

In order to maintain a sufficient liquid level in the
recondensing system tank 19, it is desirable to recondense
the gas formed by the vaporization of the liquid 21 in
the tank. This may be conveniently accomplished by
drawing off the gas through an outlet line 23 and com-
pressing the gas by means of a compressor 29 after which
the compressed gas is passed in heat exchange relation
with a cooling element 24 which may be provided with
any suitable refrigeration system, such for example as by
liquid propane in coil 25 and by liquid ethylene in coil
26. After leaving the cooling system, the compressed gas
is conducted through line 27 to a suitable expander, such

as a Joule-Thomson valve 28, to expand the compressed
gas to the pressure existing in the tank 19. Some or all
of the gas from the liquid 21 may be condensed when
reduced in temperature by the refrigeration in lines 25
5 and 26. If condensation has taken place, then the valve
28 will operate to drop the pressure of the liquid to the
pressure conditions existing in the tank 19 while a small
part of the liquid will be flashed. If no condensation
10 has taken place or if the compressed vapors are only
partially condensed in the heat exchanger, the expansion
15 of the gas to the pressures existing in the tank 19 will
be achieved with a concurrent drop in temperature and
some condensation to provide a wet gas which is intro-
duced into the tank. The condensed portion will join
the liquid surrounding the condensing coils to make up
15 for the amount vaporized while the gaseous portion will
be recycled with the released vapors through the described
condensing system thereby to maintain the desired level
of liquid in the tank 19.

20 The recondensing system, as illustrated in Figure 1,
may serve to recondense the gases from a single storage
tank or from a plurality of storage tanks. The recon-
densing system of this invention will also serve a plu-
25 rality of tanks containing different liquefied gases; but
if the gases to be stored or shipped are different, their
boiling points at the pressures at which they are main-
tained should not vary so widely that the liquid 21 in
30 the tank 19 would solidify any one or fail to liquefy an-
other. It will be apparent that when such widely vary-
ing conditions exist, use can be made of the cooling ele-
ment 24 as a recondensing system for gases which have
35 considerably higher boiling points than those stored in
tank 10 and which are to be shipped or stored over a
period of time. In such an arrangement, a system em-
bodying condensing coils and valves similar to that shown
leading from tank 10 may be used to circulate the gas
through the cooling element 24.

The system of this invention, as illustrated in Fig-
ure 1, may be varied in many ways which will occur to
40 those skilled in the art without departing from the scope
of the invention. The number of storage tanks served by
one recondensing system may be any convenient number
and the storage tanks may be arranged in various ways
45 in relation to the recondensing system. The storage and
recondensing tanks along with their insulations may be of
any suitable metal, such as stainless steel, aluminum, or
of other material, for storing liquefied gas at low tempera-
50 tures, while such additional equipment as compressors,
expansion valves, auxiliary cooling systems, etc. will be
chosen with regard to the gases to be handled and the
temperatures involved. The lines leading from the vari-
55 ous parts of the system may desirably be insulated in any
proper manner to minimize thermal losses and heat leaks.

The system embodying the features of this invention,
55 along with its possible variations, affords a means for
minimizing losses of liquefied gases which are normally
encountered in storage or in the shipment of such liquefied
gases over an extended period of time or under condi-
60 tions where heat leaks into the receptacles are rela-
tively large. These losses are minimized by the use of a
fairly simple but efficient system for recondensing the
65 gases released by vaporization of the liquefied gas during
such shipment or storage. By providing a recondensing
system which can serve a number of storage or shipping
65 receptacles and which, at the same time, permits each
receptacle to remain in a closed cycle, the problem of
metering liquefied gases to the proper receptacle is
70 eliminated and it becomes possible further to use a single
system for the reliquefaction of vapors released by tanks
containing different liquefied gases.

75 It will be understood that changes may be made in the
details of construction, arrangement and operation, as
previously described, without departing from the spirit
of the invention, especially as defined in the following
claims.

I claim:

1. Method of recovering gas boiled off from a plurality of tanks containing liquefied gas at about atmospheric pressure and for return of the liquid to each of said tanks in about the amount boiled off to maintain balance which comprises conducting said gas from each of said tanks through closed circuits passing through a liquid bath in a recondensing system at a temperature below the boiling point and above the solidifying point of said liquefied gas, thereby causing said gas to liquefy, 10 returning the resulting liquefied gas to said tanks, compressing, cooling, and expanding the vapor boiled off from said liquid bath, and returning the resulting liquefied vapor to said liquid bath.

2. Method in accordance with claim 1 wherein said 15 liquid bath consists of a quantity of said liquefied gas and said liquid bath is maintained at the required temperature by maintaining its pressure below the pressure of said liquefied gas.

3. Apparatus for recovering boil-off gas comprising a 20 plurality of tanks containing a liquefied gas which boils at a temperature far below ambient temperature, a heat

exchanger separate and apart from the tanks, means for circulating a liquid refrigerant through said heat exchanger wherein the liquid refrigerant is maintained at a temperature below the boiling point temperature of the liquefied gas but above the solidification temperature of said gas, separate closed circuit means including means separate for each of the tanks for drawing off gas that has been vaporized, means for passing said draw-off gas through said common heat exchanger in heat exchange relationship with the refrigerant, and means for returning the condensed gas from the heat exchanger to the tank from which the gas was removed.
